(57) **CLAIM**

The ornamental design for a child safety barrier, as shown and described.

DESCRIPTION

FIG. 1 is a top perspective view of a child safety barrier, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of its open state thereof; and,

FIG. 10 is an enlarged detail view of area 10 in FIG. 1.

The broken lines in the drawings illustrate the portions of the child safety barrier, which form no part of the claimed design.

The dash-dot-dash broken lines encircling the enlarged views are for annotative purposes only and form no part of the claim thereof.
